ATTORNEY

UNITED STATES PATENT OFFICE.

PHILIP HOCHHEIMER, OF NEWARK, NEW JERSEY.

PROTECTOR-RING OR BUSHING FOR BARRELS.

SPECIFICATION forming part of Letters Patent No. 735,377, dated August 4, 1903.

Application filed May 4, 1903. Serial No. 155,646. (No model.)

To all whom it may concern:

Be it known that I, PHILIP HOCHHEIMER, a citizen of the United States, residing at Newark, in the county of Essex and State of New Jersey, have invented certain new and useful Improvements in Protector-Rings or Bushings for Barrels; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

The present invention has reference to improvements in that class of flanges and protector-rings adapted for use with the bung-holes of barrels, casks, and the like; and the invention has for its principal object to provide a novel and simply-constructed protector-ring and flange of the character hereinafter set forth, the ring proper comprising a pair of separable sections, one of which is inserted in the bung-hole of the barrel or cask from the inside of the barrel or cask and has the other section tapped into the internally-arranged screw-threaded portion of the first-mentioned section, the parts being constructed and secured in their assembled positions in the bung-hole of the barrel or cask in the manner hereinafter fully described.

Other objects of this invention will be clearly evident from the following detailed description of the invention.

My invention consists, primarily, in the novel construction of protector-ring or bushing for the bung-holes of barrels or casks hereinafter more fully set forth; and, furthermore, this invention consists in the various arrangements and combinations of parts, as well as in the details of the construction thereof, all of which will be fully described in the following description of the same and then finally pointed out in the clauses of the claim appended to the present specification.

The invention is clearly illustrated in the accompanying drawings, in which—

Figure 1 is a face view of a combined flange and protector-ring or bushing, illustrating the same in its position in the bung-hole of the barrel or cask. Fig. 2 is a transverse vertical section of the combined flange and pro-

tector-ring, the said section being taken on line 2 2 in said Fig. 1; and Fig. 3 is a vertical cross-section taken on line 3 3 in said Fig. 1. Fig. 4 is a face view of a pair of detachably-connected members comprising the inner ring or bushing section, and Fig. 5 is a similar view of the said members represented in their detached or separated relation. 60

Similar characters of reference are employed in all of the said hereinabove-described views to indicate corresponding parts.

In the said drawings the reference character 1 indicates the complete protector-ring or bushing, and 2 is a portion of a barrel or cask in the bung-hole 3 of which the said device is to be arranged.

Referring now to Figs. 2 and 3 of the drawings, it will be seen that the protector-ring or bushing is made in two sections, which for sake of clearness in the following description I will designate as the "inner" section and the "outer" section on account of their affixed positions to the inner and outer surfaces of the barrel or cask when secured in their assembled positions in the bung-hole. The said inner section consists, essentially, of a pair of half sections or members 4 and 5, as will be clearly seen from an inspection of Figs. 4 and 5, the said member 4 being provided with the extensions or dowel-pins 6, adapted to be fitted in correspondingly-placed recesses or receiving-sockets 7 in the other member 5, as clearly illustrated in Fig. 5. 85

When the two sections or members 4 and 5 of the inner section have been assembled or placed upon each other, they form a ring having the smooth outer cylindrical surface 8, adapted to be snugly fitted in the bung-hole 3, as illustrated in said Figs. 2 and 3, and being provided with a shoulder or flange 9, having, preferably, a sharp marginal edge 10, which is tightly forced into the wood of the inner surface of the barrel or cask, and thereby positively holds the two members 4 and 5 of the inner bushing-section in their operative positions, as will be clearly evident. That part of the assembled members 4 and 5 which extends into the bung-hole 3 is provided upon its inner cylindrical surface with a screw-thread 11, substantially as illustrated and for the purposes to be presently described. Each section or member 4 and 5 is

100

- also provided with the oppositely-placed depressions 12 or other suitable means for the reception of the holding members of a pair of tongues or other device for holding the two members 4 and 5 in their assembled positions in the bung-hole and by proper manipulation turning the inner section of the protector-ring or bushing tightly upon the outer section. This outer section is indicated by 5 the reference character 13, and it comprises a tubular body portion 14, having its upper annular portion 15 fitted in the upper part of the bung-holes, as shown in Figs. 2 and 3, and being provided with the reduced annular portion 16, which is provided with the screw-thread 17.
- The arrangement of the internal screw-thread 11 of the two members 4 and 5 and the external screw-thread 17 of the section 13 is 10 such that the said reduced portion 16 can be securely arranged in the screw-threaded tubular portion of the two assembled sections or members 4 and 5, with the portions of the said sections or members 4 and 5 being tightly arranged 15 between the surrounding surface of the bung-hole and the outer screw-threaded surface of the outer section 13, as clearly illustrated. The said outer section 13 is also provided with a protecting-flange 18, surrounding the upper 20 portion of the said section and made with the longitudinally-extending wings or portions 19, substantially as illustrated in Figs. 1 and 2 of the drawings. The purpose of these enlarged portions of the said flange 18 is to fully 25 protect the surrounding portions of the bung-hole 3 and prevent the wood from splitting. If desired, the under surface of the said flange 18 may be provided with suitably-disposed serrations, as 20, or any other gripping 30 means, which become tightly embedded in the wood when the inner and outer protector-ring or bushing sections are tightly drawn together in their assembled positions in the bung-hole of the cask or barrel.
- 35 The manner of securing the protector-ring or bushing in the bung-hole of a barrel or cask is briefly as follows: By means of the proper tool or implement (not here described) the two separated members 4 and 5 of the inner bung-section are inserted through the bung-hole of the barrel or cask and then arranged together within the barrel near its bung-hole, so that the pins 6 will enter the recesses 7, and the assembled half sections 40 or members 4 and 5 are arranged with their screw-threaded portion within the bung-hole, the assembled sections or members 4 and 5 being held in this position by the holding members of a proper tool arranged in the registering depressions or recesses 12 of the two members 4 and 5. The reduced portion 16 of the outer member of the bushing or protector-ring is then inserted in the bung-hole from the outside of the barrel or cask and its 45 screw-thread 17 screwed part way into the screw-threaded portion 11 of the assembled half sections or members 4 and 5, the said

outer member being turned far enough that the longitudinally-extending wings 19 of the flange 18 will extend in the directions represented in Fig. 1 of the drawings and will correspond with the direction of the grain of the barrel-staves, thereby fully protecting the weakest portions of the barrel or cask near the bung-hole when the parts of the protector-ring or bushing are in their firmly-connected and operative positions in the bung-hole. Now by turning the two half sections or members 4 and 5 by means of the tool or implement which has its holding portions arranged in the depressions or recesses 12 the outer section 13 and the inner section of the protector-ring or bushing are tightly drawn toward each other, whereby the flange 9 and the flange 18 are made to tightly hug the inner and outer surfaces of the barrel or cask, as clearly illustrated, and a cheap and simply-constructed, as well as quickly-assembled, protector-ring or bushing for beer and ale barrels and other casks is the result.

I am aware that some changes may be made in the general arrangements and combinations of the parts, as well as in the details of the construction thereof, without departing from the scope of my present invention. Hence I do not limit my invention to the exact arrangements and combinations of the parts as described in the foregoing specification and as illustrated in the accompanying drawings, nor do I confine myself to the exact details of the construction of the said parts.

Having thus described my invention, what I claim is—

1. A protector-ring or bushing for barrels and casks, comprising an outer member, and an inner member consisting of a pair of separable half-sections arranged in the bung-hole from the inner side of the barrel or cask, and said outer member being arranged in the bung-hole from the outer side of the barrel or cask, and means for retaining the said members in position in the bung-hole, substantially as and for the purposes set forth.

2. A protector-ring or bushing for barrels and casks, comprising an outer member, and an inner member consisting of a pair of separable half-sections arranged in the bung-hole from the inner side of the barrel or cask, and said outer member being arranged in the bung-hole from the outer side of the barrel or cask, and both members having screw portions registering with each other, substantially as and for the purposes set forth.

3. A protector-ring or bushing for barrels and casks, comprising an outer member, and an inner member consisting of a pair of separable half-sections arranged in the bung-hole from the inner side of the barrel or cask, and said outer member being arranged in the bung-hole from the outer side of the barrel or cask, the said half-sections comprising the inner member having an internal screw-thread, and the outer member having an ex-

ternal screw-thread registering with said internal screw-thread, substantially as and for the purposes set forth.

4. A protector-ring or bushing for barrels or casks, comprising an outer member, and an inner member consisting of a pair of half-sections arranged in the bung-hole from the inner side of the barrel or cask, one of said half-sections having receiving portions, and the other half-section having projections registering with said receiving portions, and means connected with said outer and inner members for retaining them in position in the bung-hole, substantially as and for the purposes set forth.

5. A protector-ring or bushing for barrels or casks, comprising an outer member, and an inner member consisting of a pair of half-sections arranged in the bung-hole from the inner side of the barrel or cask, one of said half-sections having receiving portions, and the other half-section having projections registering with said receiving portions, and both members having screw portions registering with each other, substantially as and for the purposes set forth.

6. A protector-ring or bushing for barrels or casks, comprising an outer member, and an inner member consisting of a pair of half-sections arranged in the bung-hole from the inner side of the barrel or cask, one of said half-sections having receiving portions, and the other half-section having projections registering with said receiving portions, the said half-sections which comprise the said inner member having an internal screw-thread, and the outer member having an external screw-thread registering with said internal screw-thread, substantially as and for the purposes set forth.

7. A protector-ring or bushing for barrels and casks, comprising an outer member and an inner member, said outer member having a surrounding flange and longitudinal extensions 19, and said inner member consisting of a pair of separable half-sections arranged in the bung-hole from the inner side of the barrel or cask, and said outer member being arranged in the bung-hole from the outer side of the barrel or cask, and means for retaining said members in position in the bung-hole, substantially as and for the purposes set forth.

8. A protector-ring or bushing for barrels and casks, comprising an outer member and

an inner member, said outer member having 55 a surrounding flange and longitudinal extensions 19, and serrations upon the under surfaces of said flange and extensions, and said inner member consisting of a pair of separable half-sections arranged in the bung-hole 60 from the inner side of the barrel or cask, and said outer member being arranged in the bung-hole from the outer side of the barrel or cask, and means for retaining said members in position in the bung-hole, substantially 65 as and for the purposes set forth.

9. A protector-ring or bushing for barrels and casks, comprising an outer member and an inner member, said outer member having a surrounding flange and longitudinal extensions 19, and said inner member consisting of a pair of half-sections arranged in the bung-hole from the inner side of the barrel or cask, one of said half-sections having receiving portions, and the other half-section 75 having projections registering with said receiving portions, the said half-sections which comprise the said inner member having an internal screw-thread, and the outer member having an external screw-thread registering 80 with said internal screw-thread, substantially as and for the purposes set forth.

10. A protector-ring or bushing for barrels and casks, comprising an outer member and an inner member, said outer member having 85 a surrounding flange and longitudinal extensions 19, and serrations upon the under surfaces of said flange and extensions, and said inner member consisting of a pair of half-sections arranged in the bung-hole from the inner side of the barrel or cask, one of said half-sections having receiving portions, and the other half-section having projections registering with said receiving portions, the said half-sections which comprise the said inner 95 member having an internal screw-thread, and the outer member having an external screw-thread registering with said internal screw-thread, substantially as and for the purposes set forth.

In testimony that I claim the invention set forth above I have hereunto set my hand this 2d day of May, 1903.

PHILIP HOCHHEIMER.
